UNITED STATES PATENT OFFICE.

SAMUEL SEABURY, OF THE UNITED STATES NAVY.

BREECH-LOADING CANNON.

SPECIFICATION forming part of Letters Patent No. 425,584, dated April 15, 1890.

Application filed July 19, 1889. Serial No. 318,056. (No model.)

To all whom it may concern:

Be it known that I, SAMUEL SEABURY, lieutenant United States Navy, residing at Bergen Point, in the county of Hudson and State 5 of New Jersey, have invented a new and useful Improvement in Breech-Loading Cannon, of which the following is a specification, reference being had to the accompanying drawings.

10 This improvement relates to breech-loading cannon in which a screw breech-block, which is withdrawn in a rearward direction, is employed, with a swinging carrier or receiver hinged to one side of the breech of the gun, and into which the breech-block is withdrawn, and which serves as a guide for directing the breech-block into and from its seat in the breech and as a support for the breech-block while out of the gun. In such a gun there 15 are three movements necessary to open the breech—namely, first, the turning of the breech-block to unlock it; second, the withdrawal of the breech-block backward into the receiver, and, third, the swinging aside of the receiver with the breech-block in it. These 20 three movements have hitherto been separately performed by hand, the breech-block having been first turned to unlock it by hand and then pulled by hand back into the receiver, and the receiver having been then 25 swung aside by hand with the breech-block in it to open the breech.

The object of this improvement is to provide for the more rapid working, loading, and 30 firing of such breech-loading cannon by effecting all these movements in succession by a continuous movement of a single lever.

I will first describe my improvement with 35 reference to the drawings, and afterward point 40 out its novelty in claims.

Figure 1 is a rear view of the breech of a 45 cannon and of the breech-block, swinging breech-block carrier, and mechanism for operating said breech-block carrier embodying my invention. Fig. 2 represents a horizontal 50 sectional view corresponding with Fig. 1, taken in a plane coincident with the axis of the bore, but showing the exterior of the greater portion of the length of the breech-block. Fig. 3 is a plan view corresponding with Figs. 1 and 2. Fig. 4 represents a vertical section corresponding with Figs. 1, 2, and 3. The fig-

ures above mentioned all show the breech in its closed and locked position. Fig. 5 is a horizontal sectional view corresponding with Fig. 2, except that it shows the breech-block unlocked. Fig. 6 is a horizontal sectional view showing the breech-block withdrawn from its seat in the breech, but not yet thrown aside to open the breech for loading. Fig. 6* is a horizontal sectional view which shows the breech-block and its carrier thrown aside to the position to leave the breech open for loading. Fig. 7 is a rear view illustrating a modification of the mechanism for operating the breech-block and carrier. Fig. 8 is a plan corresponding with Fig. 7. Fig. 9 is a detail view to be hereinafter explained.

Similar letters of reference designate corresponding parts in all the figures.

I will first describe the example of my invention as illustrated by Figs. 1 to 6*, inclusive.

A designates the breech of the gun, and B the breech-block. The block is represented as having upon its exterior a mutilated screw-thread corresponding with a mutilated screw-thread in the breech to permit the block to be moved in and out of the breech and to be locked therein by turning it.

C C' C² designate the breech-block carrier, consisting of a tray C, an arm C', to which said tray is solidly attached, and two sockets C², provided on the said arm, the said sockets forming portions of the hinge by which the 8 said carrier is hinged to the breech of the gun at one side thereof. Other portions of the hinge consist of sockets D, formed in brackets D', secured to the breech of the gun at one side thereof, and a spindle E, which 9 passes through the said sockets C² and D, and for which the said sockets D D constitute bearings. The said spindle is free to turn in the said sockets within certain limits, as will be hereinafter explained. The tray C 9 conforms internally to the exterior of the breech-block and to the contour of the unmutilated portion of the screw thereof, and has at its sides longitudinal parallel tongues c, which correspond with grooves b' in the breech-block, which said grooves b' are brought exactly opposite to the said tongues c of the tray when the breech-block is turned to the position in which it is unlocked, so that when

the breech-block is drawn back it may run backward in the tray in a direction exactly parallel with the bore of the gun, the breech-block carrier and its tray being then locked, as shown in Figs. 2 and 4, to the breech of the gun and forming a continuation of the lower part of the breech-seat. The locking of the tray to the barrel is effected by means of a lever-like double catch F, which is pivoted by a pin f to the bottom of the tray. This double catch or lever has at its rear an upward projection f', which passes through a hole in the tray, and it has at its front end a downward projection f'', which engages with a hooked bolt f''' fast in the lower part of the breech of the gun, a spring f⁴ being applied between the tray and the forward part of the said lever-like catch to keep the projection f'' in engagement with the hooked bolt f''' until it is required to be disengaged.

The breech-block, the breech-block carrier, and the means of locking the carrier to the breech of the gun, so far as I have described them, are like those in common use. I will now proceed to describe my improvement whereby their more rapid operation is effected.

B' is a circular plate secured to the rear end of the breech and having upon it a toothed flange b, which is concentric with the breech-block and which gears with a straight-toothed rack a, which is fitted to run in a slideway a', firmly secured to the back of the breech for the purpose of giving the breech-block the movement on its axis necessary to lock and unlock it from its seat in the gun. This rack a is connected by a rod a² with a crank arm a³, which is fastened upon the upper end of the spindle E. The lower end of the spindle has upon it a toothed pinion E', through which it is turned to produce the movement of the arm a³ and rod a², by which the rack a is made to operate upon the toothed flange b to turn the breech-block in one direction or the other, the pinion E' being for this purpose geared with a curved rack E² on a hand-lever E³, which works horizontally on a fulcrum-pin e, secured to the lower part of the breech of the gun on the same side with the spindle E and at some distance forward of the latter.

G G designate two arms, which are fitted loosely to the spindle E between the sockets D and C² of the hinge. These arms are secured together and kept at a proper distance apart by means of an interposed sleeve g and a pin g', passing through said sleeve and fastened by a nut, which makes the said arms practically a single-forked arm. The forked ends of the said arms are connected with the breech-block in such manner that by the turning of the arms G about the axis of the spindle E the breech-block may be drawn back into the tray by the said arms and be permitted to move in a direction parallel with the bore of the gun until entirely withdrawn from its seat in the breech. The connection shown between the said arms and the breech-

block consists of a flanged ring G', which is screwed, as shown at g², Figs. 2, 4, 5, and 6, into a concentric cavity in the rear of the breech-block, horizontal slideways g³, fast upon the rear of said ring, and slides g⁴, fitted to slide on said slideways and pivoted by pins g⁵ to the ends of the said arms. This sliding connection between the arms G and the breech-block permits the breech-block to move back in lines parallel with the bore and permits the turning of the breech-block in its seat to lock and unlock it. The screw-threads of the ring G' form a permanent connection between the said ring and the block, yet permit the aforesaid turning movement of the block while the ring remains stationary. The screw-thread g² is made so fine that the small amount of movement—say one-sixth of a revolution—given to the breech-block does not materially disturb the proper connection between the said ring and the block. The arms G, the ring G', and the above-described connections between them constitute what may be termed a "breech-block retractor."

The breech-block retractor is operated to withdraw the breech-block by a projection g⁶ from the spindle E acting against the arm or arms G of the retractor. In the example of the invention shown in Figs. 1, 2, 3, 4, 5, and 6 this projection g⁶ is formed on a collar g⁷, which is keyed rigidly to the spindle by a key g⁸, fitted to mortises in the spindle and the collar, the length of said key being equal to the thickness or depth of the collar, and the mortise in the spindle being only of the same length, so that the key serves also to confine the spindle lengthwise in the hinge. The key so applied is capable of being withdrawn from its mortise in the spindle by a screw g⁹ (shown in Fig. 2) for the purpose of liberating the spindle when desired to remove it lengthwise. The projection g⁶ acts against the portion of the retractor constituted by the sleeve g. It is so arranged relatively to the arm a³, by which the breech-block is turned to lock and unlock it, that in turning the spindle E to unlock the breech-block the projection g⁶ does not come in contact with the arm G to withdraw the breech-block until after the breech-block has been unlocked and brought to a position in which its grooves b' are opposite the tongues c of the breech-block carrier.

The first part of the movement of the breech-block retractor produced by the operation of the projection g⁶ on the arm of the retractor brings the breech-block back into the tray C of the receiver to a position in which it is locked in the said receiver by means of the upward projection f' on the spring-actuated double catch f entering a notch f'', (shown in Fig. 4 and dotted in Figs. 6 and 6*), provided in the breech-block, the said catch having been previously unlocked from the fixed hooked bolt f''' by a beveled rear portion of the breech-block passing over the said upward projection f', and so depressing the rear end of the said

catch and lifting its front end from the hook of said bolt f^3 . When the notch f^* arrives over the projection f' , the said projection is caused to enter it by the downward pressure of the spring f^4 on the front end of the said catch. This method of locking and unlocking the receiver to and from the breech and of locking the breech-block to the receiver is well known and not of itself a part of this invention. The locking of the breech-block in the receiver thus effected also secures the breech-block retractor to the receiver, so that the continued movement of the retractor effected by the projection g^6 also produces the movement of the carrier. The breech-block and the retractor then being locked together, all move together, and the breech is taken from the position shown in Fig. 5 first to the position shown in Fig. 6 in bold outline and afterward to the position shown in Fig. 6*, leaving the breech of the gun open for loading. The return movement of the breech-block carrier, breech-block retractor, and breech-block is effected by the action of the projection g^6 against the trip-pin g^9 , which, as shown in Figs. 1, 2, 3, 4, and 5, is formed upon one end of a stirrup-like or double lever g^{10} , which works upon the sleeve g , hereinbefore mentioned, and to the other end of which is attached a spring g^{11} , (best shown in Figs. 5 and 6,) which presses against the outside of the collar g^7 in such manner as to throw out that end of the lever and throw the trip-pin g^9 toward the collar g^7 . As the projection g^6 moves with the spindle E from the position shown in Fig. 2, which it occupies when the breech-block is closed and locked, to the position shown in Fig. 5, which it occupies after the breech-block has been unlocked, the said projection trips the said pin g^9 or pushes it aside, so that it is inoperative, and after the said projection passes by the said pin the latter passes in front of the said projection, as shown in Fig. 5, so that when the spindle E is turned back the projection g^6 acts against the said trip-pin, and through it on the retractor to return the carrier to the breech and to produce the continued movement of the retractor to push the breech-block from the carrier into the breech of the gun.

It may be understood that by a single continuous backward movement of the lever E^3 from the position shown in dotted outline in Fig. 2 the breech-block is first turned to unlock it, is afterward drawn back by the retractor into the receiver, and after that the breech-block, retractor, and receiver are all thrown aside together to leave the breech open. The return movement of the said lever first returns the carrier and retractor to the position shown in Fig. 6, with the breech-block opposite to and in alignment with the bore of the gun, afterward continues the movement of the retractor to push the breech-block into its seat in the gun, and finally produces the turning movement of the breech-block, by which it is locked.

The modification of my improvement shown in Figs. 7, 8, and 9 differs from the example shown in Figs. 1, 2, 3, 4, 5, 6, and 6* very slightly, one essential difference being in the construction or mode of applying the rack E^2 to the lever E^3 and in the construction and means of actuating the trip-pin g^9 . The rack E^2 , (shown in Figs. 7 and 8,) instead of being rigidly connected with the lever E^3 , is pivoted to the said lever by a pin h near one end and is made to form part of a yoke E^4 , and it works upon the spindle E as a guide. The trip-pin g^9 (shown in Figs. 7, 8, and 9, of which figures 8 the last-mentioned represents a horizontal section in the line xx of Fig. 7) is fitted to slide up and down in the arm G of the breech-block retractor, a lateral projection i on the said pin working in a cam-like groove i' (see Figs. 7 and 9) in one of the stationary hinge-sockets D , and the equivalent of the projection g^6 of the first-described example is found in a downward extension of the pin g^6 , which connects the crank-arm with the rod a^2 . This downward extension acts against the upper arm G of the breech-block retractor to draw back the latter after the breech-block has been unlocked, the trip-pin g^9 being during the unlocking held down in the lower part of the cam-groove i' out of engagement with the crank-arm a^2 . As the pin g^6 begins to move the retractor-arm, the pin g^9 , moving with the said arm, is moved up into a corresponding hole in the crank-arm a^2 , and the crank-arm and the retractor-arm remain engaged by the said pin g^9 during the rest of the backward or opening movement of the retractor and breech-block carrier and also during the return or closing movement, the latter movement being effected entirely through the pin g^9 . As the return movement is completed, the pin g^9 is tripped out of the crank-arm a^2 by its projection i passing down into the lower part of the cam-groove i' and the crank-arm left free to operate the rack a to lock the breech-block.

I have shown on the lower part of the spindle below the hinge (see Figs. 3, 4, 5, and 6) a pulley P , for the purpose of producing the automatic operations of the breech-block retractor and breech-block carrier by the recoil or counter-recoil of the gun, for which purpose the said pulley would be connected by a wire rope or its equivalent with some suitable portion of the gun-carriage.

What I claim as my invention, and desire to secure by Letters Patent, is—

1. The combination, with a breech-loading cannon and a breech-block for the same, which is withdrawn in a rearward direction, of a breech-block carrier hinged to the breech, and a breech-block retractor hinged to the breech separate from said carrier to move independently of said carrier to draw the breech-block thereinto and push it therefrom, but capable of moving with said carrier while the breech-block is therein, (substantially as herein set forth.)

2. The combination, with a breech-loading

cannon and a breech-block for the same, which is withdrawn in a rearward direction, of a breech-block carrier by which the breech-block after withdrawal is moved aside out of the way of the breech, a breech-block retractor for withdrawing the breech-block from the breech into the said carrier, and a spindle supported in bearings attached to the breech and constituting a pivot upon which the said breech-block carrier and breech-block retractor are capable of separate movements, substantially as herein set forth.

3. The combination, with a breech-loading cannon and a breech-block for the same, which is locked and unlocked by turning it in the breech and is withdrawn in a rearward direction, of a breech-block carrier hinged to the breech, a breech-block retractor, also hinged to the breech, but capable of moving independently of said carrier, a locking-device for locking the breech-block, the said carrier, and the said retractor together, a pivotal spindle common to the hinges of the said carrier and retractor, a crank-arm on said spindle geared with the breech-block for turning it, and a driving projection on said spindle for actuating the said retractor, and through it the carrier, the said projection being arranged with a lost motion between it and the retractor, substantially as and for the purpose herein set forth.

4. The combination, with a breech-loading cannon, a breech-block for the same, which is locked and unlocked by turning it in the breech, a swinging breech-block carrier hinged to the breech, and a spindle which forms the pivot of the hinge of the said carrier, of a toothed rack geared with the said breech-block, and a crank-arm on said spin-

dle connected with said rack to produce the turning of the breech for locking and unlocking it, substantially as herein described.

5. The combination, with a breech-loading gun and a mutilated-screw breech-block for the same, of a breech-block retractor consisting of, first, an arm; second, a hinge by which said arm is connected with the breech of the gun; third, a ring screwed into the breech-block, and, fourth, a sliding connection between the said arm and ring, a pivot-spindle for said hinge engaging with said arm with a lost motion, a pinion on said pivot, a toothed rack geared with said pinion, and a lever for carrying said rack, said lever having its fulcrum on the breech of the gun, substantially as and for the purpose herein described.

6. The combination, with a breech-loading cannon, a breech-block for the same, which is locked and unlocked by turning it in the breech and is withdrawn in a rearward direction, and a breech-block retractor having a swinging arm which is hinged to the breech and in which the breech-block is capable of turning, of a spindle constituting the pivot of the hinge of the said retractor, and having a rigid projection for acting upon the swinging arm of the retractor with a lost motion to withdraw the breech-block, and a trip-pin attached to said arm to engage with said projection for the return movement of the retractor, but to be tripped during the withdrawing movement, substantially as herein set forth.

SAMUEL SEABURY.
